NUT

Harald F. Gade, Philadelphia, Pa., assignor to
Standard Pressed Steel Co., Jenkintown, Pa.,
a corporation of Pennsylvania

Application August 18, 1948, Serial No. 148,171

Term of patent 14 years

(Cl. D54—9)

To all whom it may concern:

Be it known that I, Harald F. Gade, a citizen of the United States, residing in Philadelphia, Philadelphia County, Pennsylvania, have invented a new, original, and ornamental Design for a Nut, of which the following is a specification, reference being had to the accompanying drawing forming a part thereof.

In said drawing:

Fig. 1 is a view in perspective of the nut, showing my new design;

Fig. 2 is an enlarged side elevational view; and
Fig. 3 is an enlarged top plan view.

I claim:

The ornamental design for a nut, as shown.

HARALD F. GADE.
